Primary Examiner — Melanie Pellegrini

(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

1.8 : Perspective of the bracelet open

The bracelet comprises two substantially semi-circular rigid elements that are joined by a hinge at one end and interconnected at the other end by a clasp comprising a pivoting locking element provided with a decorative embossed pattern resembling an anchor chain link.
